Primary Examiner — Philip S Hyder(74) *Attorney, Agent, or Firm* — John Rizvi; John Rizvi, P.A.—The Patent Professor®(57) **CLAIM**

I claim the ornamental design for a support wedge, as shown and described.

DESCRIPTION

FIG. 1 is a front isometric view of a support wedge showing my new design;

FIG. 2 is a rear isometric view thereof;

FIG. 3 is a front elevation view thereof;

FIG. 4 is a back elevation view thereof;

FIG. 5 is a right side elevation view thereof;

FIG. 6 is a top side plan view thereof; and,

FIG. 7 is a bottom side plan view thereof.

A left side elevation view has been omitted; as it is a mirror image of the right side elevation view of FIG. 5.

The broken contour lines form no part of the claimed design.
